Primary Examiner — Rosemary K Tarcza
Assistant Examiner — Seth David Kumpf(57) **CLAIM**

The ornamental design for a power adapter, as shown and described.

DESCRIPTION

FIG. 1 is a perspective view of a power adapter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view showing the power adapter in a use state.

The broken lines in the drawings are for the purpose of illustrating portions of the power adapter that form no part of the claimed design.

1 Claim, 9 Drawing Sheets(56)
